UNITED STATES PATENT OFFICE.

CLARENCE A. BODDIE, OF PITTSBURGH, PENNSYLVANIA, ASSIGNOR TO WESTINGHOUSE ELECTRIC & MANUFACTURING COMPANY, A CORPORATION OF PENNSYLVANIA.

FURNACE-REGULATOR SYSTEM.

Application filed December 3, 1919. Serial No. 342,175.

To all whom it may concern:

Be it known that I, CLARENCE A. BODDIE, a citizen of the United States, and a resident of Pittsburgh, in the county of Allegheny and State of Pennsylvania, have invented a new and useful Improvement in Furnace-Regulator Systems, of which the following is a specification.

My invention relates to regulator systems 10 and particularly to regulator systems for governing the operation of the movable electrodes in electric furnaces.

One object of my invention is to provide a furnace-regulator system that shall govern 15 the movements of each electrode in accordance with the current flowing through it to maintain a substantially constant arc and that shall be provided with a two-fold means for preventing so-called hunting action.

20 In operating electric furnaces, it is customary to govern the movement of each electrode in accordance with the current flowing through it and thus maintain a substantially constant electrode arc. However, such means 25 for regulating the furnace is unsatisfactory unless some means is provided for insuring the system against hunting action.

In a furnace-regulator system constructed 30 in accordance with my invention, each movable electrode is provided with a motor for raising and lowering it and a regulator is provided for effecting the operation of the motor in a clockwise and in a counter-clockwise direction in accordance with the value 35 of the current flowing through the electrode. The regulator comprises a main control element having a main and an auxiliary electromagnet and two switches which are governed by the main control element for controlling the operation of the electrode motor.

40 The main magnet embodies a winding which is energized in accordance with the current flowing through the associated electrode and is provided with taps through 45 which circuits are selectively completed by the switches for varying the active number of turns in the winding of the main magnet to change its setting and prevent the so-called hunting action. The auxiliary electromagnet 50 preferably comprises two windings which are constantly energized and a third winding which is disposed between the first two windings and is energized in accordance with the counter-electromotive force of the 55 electrode motor. Such arrangement of

windings in the auxiliary electromagnet provides a polarized electromagnet so that the magnet operates in accordance with the direction of current flow through the motor armature.

A mechanical or energy-transmitting connection is provided between the main and the auxiliary magnet whereby the main magnet is influenced in accordance with the operation of the auxiliary magnet to prevent 65 hunting action. Each of the two switches, which are operated by the main control element for governing the direction of rotation of the electrode motor, comprise three windings. One of the windings serves as a holding winding for biasing the switch to a released position, and the other two windings serve to neutralize the holding winding and for operating the switch to an operative position. The switches not only serve to govern 70 the direction of rotation of the motor and to vary the energization of the main magnet for preventing hunting action, but also to complete a dynamic-braking circuit through the electrode motor when simultaneously released.

75 In the accompanying drawing, Figure 1 is a diagrammatic view of a regulator system embodying my invention, and Fig. 2 is a similar view of a modification of the system 80 shown in Fig. 1.

85 Referring to Fig. 1 of the drawing, an electric furnace 1, comprising a receptacle 2, containing a bath of material 3, and three movable electrodes 4, 5 and 6, is directly 90 connected to a three-phase supply circuit comprising conductors 7, 8 and 9.

95 Each of the movable electrodes is provided with a motor for raising and lowering it and a regulator for governing the operation of the electrode motor in accordance with the value of the current flowing through the associated electrode. Inasmuch as the motors and regulators associated with the various 100 movable electrodes are similar in construction and operation, it is deemed sufficient to describe the construction and operation of but one motor and one regulator, namely, the motor and regulator which are associated with the movable electrode 6.

105 An electric motor 10, comprising an armature 11 and a field-magnet winding 12, is provided for raising and lowering the electrode 6. The field-magnet winding 12 is directly connected across a supply circuit 110

comprising conductors 13 and 14, and the armature 11 is selectively connected across the supply conductors 13 and 14 by means of switches 15 and 16. Switches 15 and 16 will be more fully described hereinafter—but for a complete disclosure thereof, reference is made to my copending application, Serial No. 378,372, filed May 4, 1920. The armature 11 of the motor is mechanically connected to the electrode 6 in any suitable manner, as by means of a winding reel 17 and a flexible connector 18 which passes over a pulley 19.

A main control element 20, comprising a main magnet 21 and an auxiliary magnet 22, is provided for governing the operation of the switches 15 and 16 in accordance with the current flowing through the electrode 6. The main magnet 21 comprises a winding 23 which is connected to the three-phase supply conductor 9 by means of a current transformer 24 in order to be energized in accordance with the current flowing through the electrode 6. A plurality of taps 25, 26 and 27 extend from the winding 23 for a purpose to be hereinafter set forth. A core armature 28, which is pivotally connected to a contact arm 29 and is operated by the winding 23, is provided with a piston 30 which operates within a cylinder 31 for changing the setting of the main magnet 21, under certain conditions, to prevent hunting action by the regulator. The contact arm 29, which is fulcrumed at 32, carries a main contact member 33 that is adapted to engage contact members 34 and 35 according to the operative position of the main magnet 21.

The auxiliary electromagnet 22 comprises two windings 36 and 37, which are directly connected across the supply conductors 13 and 14, and a winding 38 which is disposed between the windings 36 and 37 and which is connected across the armature 11 of the motor 10 in order that it may be energized in accordance with the counter electromotive force of the electrode motor. The three windings 36, 37 and 38 operate upon a core armature 39 which is supported by a spring member 40 and is provided with a piston 41. The piston 41 is located for operation within a cylinder 42. The two cylinders 31 and 42 are connected by means of a pipe 43 which is filled with any suitable fluid preferably oil, in order that the operation of the main magnet 21 may be influenced in accordance with the operation of the auxiliary magnet 22.

The movement of the piston 41 within the cylinder 42, in accordance with the operation of the auxiliary magnet 22, varies the pressure that is exerted upon the piston 30, and, accordingly, changes the setting of the main magnet 21. The operation of the auxiliary magnet 22 is so controlled by the winding 38 as to change the setting of the

main magnet 21 in a manner to prevent any hunting action. The two windings 36 and 37 are so disposed upon the core armature 39 that they effect no operation of the core armature, but they serve to polarize the electromagnet for operation by the winding 38 in accordance with the direction of rotation of the motor 10.

The switch 15 comprises three windings 44, 45 and 46 and a pivotally mounted armature 47 which is controlled by the windings 44, 45 and 46. The winding 46 is connected across the supply conductors 13 and 14 in series with a resistor 48 and serves to bias the armature 47 to a released position. The windings 44 and 45 are connected across the supply conductors 13 and 14 upon engagement between the main contact members 33 and 35 and serve to neutralize the effect of the winding 46 and to move the armature 47 to an operative position for operating the motor 10 in a counter-clockwise direction. The winding 44 operates on a core armature 49 which is pivotally connected to an arm 50 of the armature 47. The armature 47, which is fulcrumed at 51, comprises two arms 50 and 52, which are angularly disposed in relation to each other, and an interlock switch 53 which is connected to the arm 50. When the armature 47 is in a released position, as shown on the drawing, the arm 52 engages the contact member 54 for completing a dynamic-braking circuit through the armature 11 of the motor 10 and, upon movement of the armature 47 to an operative position, the arm 50 engages the contact member 55 for connecting the armature 11 across the supply conductors 13 and 14 to effect rotation of the motor 10 in a counter-clockwise direction. The interlock switch member 53, which is connected to the arm 50, serves to close a short circuit across that portion of the winding 23 which is included between the taps 26 and 27 for preventing hunting action of the regulator when the electrode is being raised from the bath of material.

The switch 16 comprises three windings 56, 57 and 58 which control the operation of an armature 59. The armature 59, which is fulcrumed at 60, comprises two arms 61 and 62 that are angularly disposed relative to each other. The contact arm 62, in the released position of the switch, engages a contact member 63 to complete a dynamic-braking circuit through the armature 11 of the motor 10. The arm 61, upon operation of the switch, engages a contact member 64 to connect the armature 11 across the supply conductors 13 and 14 to effect clockwise rotation of the motor. The arm 61 is provided with an interlock switch member 65 which serves, upon operation of the switch 16, to open a short-circuit which normally exists across that portion of the

winding 23 which is included between the taps 26 and 25. Thus, the setting of the main magnet 21 is changed to prevent hunting action when the electrode 6 is being lowered in the furnace. The winding 58 is permanently connected through the resistor 48 across the supply conductors 13 and 14 for biasing the armature 59 to a released position. The windings 56 and 57 are connected across the supply conductors 13 and 14 upon engagement between the main contact members 33 and 34 and serve to neutralize the holding winding 58 and to move the armature 59 to an operative position. The winding 56 operates on a core armature 66 which is pivotally connected to the switch arm 61 of the armature 59.

If current below normal value flows through the electrode 6, the energization of the winding 23 is decreased for operating the switch arm 29 to effect engagement between the contact members 33 and 34. Upon engagement between the contact members 33 and 34, a circuit which is completed for operating the switch 16, extends from the supply conductor 13 through the switch arm 29, contact members 33 and 34 and the windings 56 and 57 to the supply conductor 14. Thereupon, the holding power of the winding 58 is neutralized by the winding 57, and the winding 56 moves the switch arm 61 into engagement with the contact member 64. A circuit is completed which extends from the supply conductor 14 through the contact member 54, switch arm 52, armature 11 of the motor 10, switch arm 61 and the contact member 64 to the supply conductor 13. Accordingly, the motor is operated in a clockwise direction to lower the electrode 6 in the furnace and to increase the current flow through the electrode.

If no means were provided for preventing any hunting action on the part of the regulator, the motor 10 would continue to lower the electrode in the furnace until a normal amount of current was flowing through the electrode for increasing the energization of the main magnet to effect separation of the main contact members 33 and 34. Consequently, the moving parts of the regulator and the armature of the motor 10 would overtravel to lower the electrode 6 beyond the point necessary to obtain normal current flow through the electrode circuit. In order to prevent such overtravel and the consequent hunting action, the interlock switch member 65 is operated simultaneously with the motor 10 for opening the short-circuit which obtains across that portion of the winding 23 which is included between the taps 25 and 26. Thus, the energization of the main magnet 21 is increased to change the setting of such magnet and to effect operation of the contact arm 29 to sepa-

rate the contact members 33 and 34 just prior to the obtaining of normal current flow through the circuit of the electrode 6.

Hunting action on the part of the regulator is not only prevented by varying the energization of the main magnet 21 but is also insured against by the operation of the auxiliary magnet 22. Thus, in the case under consideration, the winding 38 of the auxiliary magnet is energized by the counter-electromotive force of the motor 10 for moving the core armature 39 and the piston 41 downwardly and, consequently, the pressure upon the bottom of the piston 30 of the main magnet 21 is increased to change the setting of such magnet and, thereby, its tendency to effect a separation of the contact members 33 and 34 just prior to the obtaining of normal current flow through the electrode 6. It will be noted that, inasmuch as the auxiliary magnet 22 operates as a polarized electromagnet, it is possible to operate the piston 41 in either direction, as desired, in accordance with the direction of rotation of the motor 10. In the case under consideration, it is assumed that the plunger 41 is lowered when the motor is operated in a clockwise direction and is raised when the motor is operated in a counter-clockwise direction.

If current above normal value flows through the electrode 6, the energization of the main magnet 21 is increased to effect engagement of the contact members 33 and 35. Upon engagement of the contact members 33 and 35, a circuit, which is completed for operating the magnet 15, extends from the supply conductor 13, through the contact arm 29, contact members 33 and 35, and the windings 44 and 45, to the supply conductor 14. The winding 45 is energized for neutralizing the effect of the winding 46 upon the armature 47, and the winding 44 is energized for moving the switch arm 50 into engagement with the contact member 55. Thereupon, a circuit is completed which extends from the supply conductor 14, through the contact member 63, switch arm 62, armature 11, switch arm 50 and the contact member 55 to the supply conductor 13. Accordingly, the motor 10 is operated in a counter-clockwise direction for raising the electrode 6 to reduce the current flow through the electrode circuit.

In order to prevent hunting action when the motor 10 is being operated in a counter-clockwise direction to raise the electrode 6, the interlock switch member 53 is operated simultaneously with the motor 10 to short-circuit that portion of the winding 23 which is included between the taps 26 and 27. Thus, the energization of the main magnet 21 is decreased to change the setting of such magnet in order to effect separation of the contact members 33 and 35 just prior to the

obtaining of normal current flow through the electrode 6.

The operation of the motor also serves to effect operation of the auxiliary magnet 22 for preventing any hunting action by the regulator. Thus, the operation of the motor 10 in the counter-clockwise direction energizes the winding 38 in a manner to raise the core armature 39 and the piston 41. The 10 raising of the piston 41 reduces the pressure which is exerted upon the bottom of the piston 30 and, consequently, changes the setting of the magnet 21 to permit separation of the contact members 33 and 35 just prior to the 15 obtaining of normal current flow through the electrode 6.

The system illustrated in Fig. 2 of the drawing is similar in operation and somewhat similar in construction to the system 20 illustrated in Fig. 1 of the drawing and, accordingly, a complete description of the operation of the system shown in Fig. 2 is deemed unnecessary. Moreover, similar parts in Fig. 2 of the drawing have been 25 referred to by corresponding reference numerals. The system shown in Fig. 2 of the drawing differs from the system shown in Fig. 1 chiefly in the mechanical connection between the main and the auxiliary electro- 30 magnets and in the operation of the switches which are operated by the main control element.

Referring to Fig. 2 of the drawing, the main and the auxiliary electromagnets 21 and 22, which are respectively provided with dash pots 70 and 71 for adjusting their operation, are connected to opposite ends of a contact arm 72. The contact arm 72 is fulcrumed at 73 and it carries a main contact 35 member 74 which engages contact members 75 or 76, according to the operative position of the main control element. Two spring members 77 and 78 are connected to opposite ends of the contact arm 72 for 40 maintaining it in a neutral position when the main control element is de-energized. Two switches 79 and 80 are governed by the main control element for operating the motor 10 in a counter-clockwise and in a 45 clockwise direction to govern the amount of current flowing through the electrode 6. The switch 79 comprises a winding 79^a which is connected across the supply conductors 13 and 14 upon engagement between 50 the contact members 74 and 76. The winding 79 controls a core armature 81 which is directly connected to two switch members 82 and 83 and two interlock switch members 84 and 85. The two switch members 82 and 55 83 serve to connect the armature 11 across the supply conductors 13 and 14 for operating the motor 10 in a counter-clockwise direction. The interlock switch 84, upon 60 operation of the switch 79, completes a circuit for short-circuiting that portion of the 65

winding 23 which is included between the taps 25 and 26 for reducing the energization of the main magnet 21 to prevent any hunting action.

The switch 80 comprises a winding 86, 70 which is connected across the supply conductors 13 and 14 upon engagement between the main contact members 74 and 75, and a core armature 87, which is controlled by the winding 86. The core armature 87 is directly connected to two switch members 88 and 89 and two interlock switch members 90 and 91. The two switch members 88 and 89, upon operation of the switch 80, connect the armature 11 across the supply conductors 13 and 14 for operating the motor 10 in a clockwise direction. The interlock switch member 90, upon operation of the switch 80, serves to open a short-circuit which normally obtains across that portion 85 of the current winding 23 which is included between the taps 26 and 27 and, accordingly, to increase the energization of the main magnet 21 and prevent any hunting action 90 when the electrode 6 is being lowered in the furnace.

When the two switch members 79 and 80 are simultaneously de-energized, the interlock switch members 85 and 90 connect the energizing winding of the brake relay 92 95 across the supply conductors 13 and 14. Upon operation of the brake relay 92, a dynamic-braking circuit for the armature 11 is completed through a resistor 93. Thus, when the motor 10 is operated in a counter-clockwise or in a clockwise direction for respectively raising or lowering the electrode 6, a dynamic-braking circuit is completed upon the release of the switch 79 or the switch 80, as the case may be, for effecting 100 a quick stopping of the motor.

If current above normal value flows through the electrode 6, the energization of the main magnet 21 is increased to operate the contact arm 110 72 and effect engagement between the contact members 74 and 76. Upon engagement between the contact members 74 and 76, a circuit is completed from the supply conductor 13 through the contact arm 72, 115 contact members 74 and 76 and the winding 81 to the supply conductor 14. The switch 79 is operated and a circuit is completed which extends from the supply conductor 13 through the switch member 82, armature 11, and the switch member 83 to the supply conductor 13. Thereupon, the motor 10 is operated in a counter-clockwise direction for raising the electrode 6 to decrease the 120 current flow through it.

The interlock switch member 84 is operated simultaneously with the motor 10 for short-circuiting a portion of the winding 23 of the main magnet 21 in order to change 125 the setting of the main control element and 130

thus prevent the so-called hunting action. The setting of the main control element 20 is so changed that separation of the contact members 74 and 76 is effected just prior to the obtaining of normal current flow through the electrode 6, and, consequently, overtravel of the various moving parts of the regulator and of the motor 10 is prevented.

10 Hunting action is not only insured against by the variation in the energization of the main magnet 21 but also by the operation of the auxiliary magnet 22. The auxiliary magnet is similar in construction and operation to the auxiliary magnet shown in Fig. 1 of the drawing. However, in the system shown in Fig. 2, the auxiliary magnet is directly connected to the contact arm 72 and it opposes the action of the main magnet 21 through the contact arm. In the case under consideration, the auxiliary magnet 22 is operated to separate the contact members 74 and 76 when the motor is being operated in a counter-clockwise direction. It is to be understood that the effect of the variation in the energization of the main magnet 21 and of the auxiliary magnet 22 is so adjusted as to separate the contact members 74 and 76 just prior to the obtaining of normal current flow through the electrode 6.

If the current flow through the electrode 6 is below normal value, the energization of the main magnet 21 is decreased to effect engagement between the contact members 74 and 75. Upon engagement between the contact members 74 and 75, a circuit is completed from the supply conductors 13 and 14 for operating the switch 80 to effect clockwise rotation of the motor 10. Upon operation of the motor 10 in a clockwise direction, the electrode 6 is lowered in the furnace to increase the current flow through the electrode circuit. The interlock switch member 90 is operated simultaneously with the motor 10 for opening the short-circuit which normally obtains across that portion of the winding 23 which is included between the taps 26 and 27 for increasing the energization of the main magnet 21 to change its setting. The setting of the main magnet 21 is changed in order that the main contact members 74 and 75 shall be separated just prior to the obtaining of normal current flow through the electrode 6 and, accordingly, prevent overtravel with the consequent hunting action. At the same time, the auxiliary magnet 22 is energized by the counter-electromotive force of the motor 10 to separate the contact members 74 and 75 and to assist in preventing hunting action.

From the above description, it will be noted that each electrode motor is operated in accordance with the current flowing through the associated electrode for main-

taining a substantially constant electrode arc, and that the active turns of the main magnet are not only varied for preventing hunting action, but the auxiliary magnet is mechanically connected to the main magnet for changing the setting of such magnet to prevent hunting action.

70 In the claims, where the terms "energy transmission connection" or "mechanical connection" are used, it is to be understood that any non-electrical connection is comprehended that will permit the electromagnets to function as herein described.

75 In my copending application, Serial No. 319,906, filed August 26, 1919, I have illustrated, described, and claimed a furnace-regulator system having another means for preventing hunting action.

80 Modifications in the system and arrangement and location of parts may be made within the spirit and scope of my invention, and such modifications are intended to be covered by the appended claims.

I claim as my invention:

1. In a furnace-regulator system, the combination with a movable electrode, a motor for raising and lowering the electrode, and a main magnet for governing the operation of said motor in accordance with the current flowing through the electrode, of means for mechanically and electrically governing the operation of the main magnet to prevent hunting action.

100 2. In a furnace-regulator system, the combination comprising a movable electrode, a motor for raising and lowering said electrode, a main magnet operated in accordance with electrode circuit conditions for controlling said motor, and means for electrically and mechanically influencing the 105 operation of the main magnet to prevent hunting action.

110 3. In a furnace-regulator system, the combination comprising a movable electrode, means comprising an electromagnet for governing the operation of said electrode in accordance with electrode circuit conditions, and means for electrically and mechanically influencing the operation of said magnet to prevent hunting action.

115 4. In a furnace-regulator system, the combination comprising a movable electrode, means comprising an electromagnet for governing the operation of said electrode in accordance with electrode-circuit conditions and two separate means for influencing the operation of said magnet to prevent hunting action.

120 5. In a furnace-regulator system, the combination comprising a movable electrode, a motor for raising and lowering the electrode, means comprising a main magnet for governing the operation of said motor in accordance with electrode-circuit conditions to maintain a constant electrode arc, means

for varying the energization of said magnet to prevent hunting action, and mechanical means varied in accordance with the operation of said motor for influencing the magnet to prevent hunting action.

6. In a furnace-regulator system, the combination with a movable electrode, a motor for raising and lowering the electrode, and means comprising a main magnet energized 10 in accordance with the current flowing through the electrode for maintaining a constant electrode arc, of means comprising two switches for varying the active number of turns in said magnet to prevent hunting 15 action, and an auxiliary magnet controlled by said switches and acting on the main magnet to prevent hunting action.

7. In a furnace-regulator system, the combination with a movable electrode, means 20 for raising and lowering said electrode, and a main magnet for governing the operation of said means, of an auxiliary magnet, and means for influencing the operation of the main magnet indirectly through the auxiliary magnet and for directly influencing 25 the operation of the main magnet to prevent hunting action.

8. In a furnace-regulator system, the combination with a movable electrode, a motor 30 for raising and lowering the electrode, and a main magnet for controlling the operation of the motor in accordance with the current flowing through the electrode, of an auxiliary magnet, and means for controlling 35 the auxiliary magnet to mechanically influence the main magnet and prevent hunting action and for varying the active number of turns in the winding of the main magnet to prevent hunting action.

40 9. In a furnace-regulator system, the combination with a movable electrode, a motor for raising and lowering said electrode, and a main magnet for controlling the operation of said motor in accordance with the current 45 flowing through the electrode, of an auxiliary magnet having two constantly energized windings and a third winding disposed between said two windings, means for energizing said third winding in accordance 50 with the operation of said motor, and a mechanical connection between said magnets for influencing the main magnet in accordance with the operation of the auxiliary magnet to prevent hunting action.

55 10. In a furnace-regulator system, in combination, a movable electrode, means comprising a main magnet for controlling the operation of the movable electrode in accordance with the current flowing through 60 it, an auxiliary magnet having a mechanical connection to the main magnet, and means for operating the auxiliary magnet in accordance with the counter-electromotive force of the motor to influence the main magnet and prevent hunting action.

11. In a furnace-regulator system, the combination with a movable electrode, a motor for operating the electrode, and means comprising a main magnet for controlling the operation of the motor in accordance with the current flowing through the electrode, of an auxiliary magnet, means for polarizing the auxiliary magnet and for operating it in accordance with the operation of the motor, and means for influencing 70 the main magnet in accordance with the operation of the auxiliary magnet to prevent hunting action.

12. In a furnace-regulator system, the combination with a movable electrode, a motor for operating the electrode and means comprising a main magnet for controlling the operation of the motor in accordance with the current flowing through the electrode, of an auxiliary magnet, means for operating said auxiliary magnet in accordance with the counter-electromotive force of the motor, and a mechanical connection between said magnets for operating the main magnet in accordance with the operation of 80 the auxiliary magnet to prevent hunting 85 action.

13. In a furnace-regulator system, the combination with a movable electrode, and a motor for raising and lowering said electrode, of means comprising two switches for controlling the operation of said motor in accordance with the current flowing through the electrode to maintain a constant electrode arc, each of said switches comprising 95 a constantly energized winding for biasing the switch to a released position and two windings for operating the switch and for neutralizing said first winding.

14. In a furnace-regulator system, the combination with a movable electrode, and a motor for operating said electrode, of a main control element for controlling the operation of said motor in accordance with the current flowing through the electrode, said element comprising a main magnet energized in accordance with the current flowing through the electrode and an auxiliary polarized electromagnet having a polarizing and an operating winding, means for varying the energization of said main magnet to prevent hunting, and means for varying the energization of the operating winding of said auxiliary magnet in accordance with the energization of the electrode motor to prevent hunting action.

15. In a regulator system, the combination with a supply circuit and an energy-translation device associated therewith, of regulator mechanism therefor comprising a control electromagnet and a plurality of independent devices associated therewith for preventing hunting action in said system.

16. In a regulator system, the combination with a supply circuit and an energy-trans-

- lating device associated therewith, of regulator mechanism therefor comprising a control electromagnet and two means for preventing hunting action in said system.
- 5 17. In a regulator system, the combination with a supply circuit, a resistance-varying member associated therewith, and means for operating said member, of regulator mechanism therefor comprising a plurality 10 of electromagnets and means associated with each of said electromagnets for preventing hunting action in said system.
18. In a furnace-regulator system, the combination with an electrode, and a motor 15 for raising and lowering said electrode, of regulator mechanism therefor comprising a plurality of electromagnets, and means associated with each of said electromagnets for preventing hunting action in said system.
19. In a furnace-regulator system, the combination with a movable electrode and a motor for moving said electrode, of regulator mechanism therefor controlled in accordance 20 with an electrical characteristic of the electrode circuit and two means for preventing hunting action in said system.
20. In a furnace regulator, the combination with a movable electrode, a motor for moving said electrode, and a plurality of 25 switches for controlling the operation of said motor, each of said switches having a contact arm, electrical means for operating said arm to one position, and a second electrical means adapted to actuate said arm 30 to a second position, both of said means co-operating directly with said arm, of regulator mechanism adapted to control the operation of said switches in accordance with an electrical characteristic of the electrode 35 circuit.
21. In a furnace regulator, the combination with a movable electrode, a motor for moving said electrode, and a plurality of switches for controlling the operation of 40 said motor, each of said switches having a contact arm, means for operating said arm to one position and electrical means for actuating said arm to a second position and
- holding the same in said second position, of regulator mechanism adapted to control 50 the operation of said switches in accordance with an electrical characteristic of the electrode circuit.
22. In a furnace regulator, the combination with a movable electrode, a motor for moving said electrode, switching means for controlling the operation of said motor, said switching means comprising means for operating said switch to actuate said motor and also additional means for returning the switch to its non-actuating position, of regulator mechanism adapted to control the operation of said switching means in accordance with an electrical characteristic of the electrode circuit.
23. In a furnace regulator, the combination with a movable electrode, a motor for moving said electrode, and switching means movable in two directions for controlling the operation of said motor and a dynamic 70 braking circuit therefor, said switching means comprising means for actuating the switch in both directions and retaining the same in one position, of regulator mechanism adapted to control the operation of 75 said switching means in accordance with an electrical characteristic of the electrode circuit.
24. In a furnace regulator, the combination with a movable electrode, a motor for 80 moving said electrode, and switching means for controlling the operation of said motor and a dynamic-braking circuit therefor, said switching means being normally positively actuated to complete said dynamic-braking 85 circuit and having means for actuating the same to initiate the operation of said motor, of regulator mechanism adapted to control the operation of said switching means in accordance with an electrical characteristic of the electrode circuit.

In testimony whereof, I have hereunto subscribed my name this 29th day of November, 1919.

CLARENCE A. BODDIE.
